UNITED STATES PATENT OFFICE.

HARRY J. WILLIAMS, OF MERIDEN, CONNECTICUT.

CORK-EXTRACTOR.

SPECIFICATION forming part of Letters Patent No. 619,648, dated February 14, 1899.

Application filed October 6, 1898. Serial No. 692,825. (No model.)

To all whom it may concern:

Be it known that I, HARRY J. WILLIAMS, of Meriden, in the county of New Haven and State of Connecticut, have invented certain

5 new and useful Improvements in Cork-Extractors; and I do hereby declare the following to be a full, clear, and exact description of the same, reference being had to the accompanying drawings, forming a part of this
10 specification, and to the letters of reference marked thereon.

The invention relates to improvements in power cork-extractors or such as are designed to be attached or clamped to a counter or
15 table and operated by means of a handle or lever; and the objects of the invention are to produce a simple and powerful mechanism which will with one reciprocation of the handle force the corkscrew into the cork, extract the cork from the bottle, and discharge
20 the cork from the screw, leaving the parts in position for the next succeeding operation.

Referring to the accompanying drawings, Figure 1 is a vertical sectional view, partially
25 in elevation, showing the position of the parts when the handle or lever has been moved forwardly and the corkscrew forced into a cork within the mouth of the bottle. Fig. 2 is a similar view showing the position of the parts
30 when the cork has been withdrawn from the mouth of the bottle and the handle or lever has moved part way back to normal position. Fig. 3 is a similar view illustrating the position of the parts in their normal position or
35 when the handle has been moved to a position to discharge the cork and to leave the parts ready for a subsequent operation.

Like letters of reference in the several figures indicate the same parts.

40 The letter A indicates the frame or body of the instrument, which is preferably formed with a clamp B for attachment to a counter or like support and which may be varied indefinitely to suit the particular conditions
45 under which the device is used. The front portion of the frame or body A is made in the form of a cylinder A', preferably somewhat inclined to the perpendicular for convenience in presenting a bottle to the extracting mechanism.
50 Immediately in rear of this cylinder a chamber A² is formed for the reception or accommodation of a worm-wheel C, mounted

on a squared portion of a shaft c, forming a lateral projection of a handle or lever C', by means of which the extracting mechanism is 55 operated.

Working within the cylinder A' is a screw-threaded shank D, the threads of which mesh with the worm-wheel C, adapting the shank D to be both moved longitudinally and rotated 60 by the action of the worm-wheel, the teeth on the shank D serving both as a rack and as worm-teeth in accomplishing these motions. The lower end of the shank D terminates in or has attached to it in any suitable manner 65 a corkscrew E, the spiral of which runs in an opposite direction from the thread on the shank D. Thus if the threads on the shank D are left-handed threads the spiral of the corkscrew is a right-handed spiral, and vice 70 versa. The corkscrew works through a nut F, mounted in the lower end of the cylinder A' and held against rotation by a screw f, working in a slot f' in the cylinder, which slot f' also permits the said nut to move longitudinally in the cylinder a distance corresponding to the necessary longitudinal movement of the corkscrew in withdrawing the cork from the bottle, and the action of this nut F when the shank and corkscrew are thrust down is 75 80 to cause the said corkscrew to rotate forwardly and enter a cork if the same is presented in proper position.

The longitudinal movement of the shank and corkscrew in an upward direction is 85 limited by a cap or plug G in the upper end of the cylinder, and in order to eliminate friction in the rotation of the shank and corkscrew when at the upward extreme of its longitudinal movement the end of the shank is 90 preferably reduced, as at d, and adapted to coöperate with a cone bearing in the under side of the cap at g, Fig. 2. If desired, however, a ball-bearing of any well-known construction may be introduced in the cap, as indicated, for instance, at g' in Fig. 1, it being understood, however, that any well-known form of bearing may be substituted without departing from the invention in the slightest.

With a device constructed as thus described 100 when it is desired to extract a cork, assuming that the parts are in the normal position indicated in Fig. 3, the bottle is presented to the lower end of the cylinder and the handle

C' brought over to the front of the device or to the position indicated in Fig. 1, the action of the worm-wheel C upon the shank D tending, first, to advance the shank and corkscrew 5 through the nut F, and by such movement the nut F will cause the screw to rotate forwardly and penetrate the cork, and, secondly, by reason of the inclination of the teeth on the shank D the tendency of the said worm- 10 wheel C will be to cause the said shank and corkscrew to rotate, thus there is imparted to the shank and corkscrew a tendency to rotate forwardly through two separate mechanisms—that is to say, through the action of the 15 worm-wheel and the worm and through the action of the nut F, operating directly on the corkscrew. The screw having now penetrated the cork to the position indicated in Fig. 1, a reverse movement of the handle will 20 cause the worm-wheel and threaded shank to operate as a rack and pinion, withdrawing the cork from the mouth of the bottle and raising the nut F to the upper limit of its movement or until the upper end of the shank 25 strikes the bearing g, when its further upward longitudinal movement will be arrested, when the worm-wheel and threaded shank will again operate to rotate the said shank and corkscrew in a reverse direction, such reverse 30 rotation causing the nut F to travel down the corkscrew and drive the cork off from the same, the parts then assuming, as the handle is drawn backwardly, the position indicated in Fig. 3, ready for a subsequent operation.

35 Having thus described my invention, what I claim as new is—

1. In a cork-extractor, the combination with a frame or housing, of a threaded shank working in said frame or housing, a corkscrew forming a prolongation of said threaded shank, a longitudinally-movable nut through which said corkscrew works, and a toothed wheel meshing directly with the threaded shank with a handle or lever for reciprocating said 40 wheel; substantially as described.
2. In a cork-extractor the combination with a frame or housing having a cylinder therein, of a screw-threaded shank working longitudinally in said cylinder, a corkscrew-spiral

forming a prolongation of said screw-threaded shank, a nut working longitudinally in said cylinder and surrounding the corkscrew-spiral, a bearing for limiting the upward movement of the shank and screw, a toothed wheel journaled in the frame or housing and meshing directly with the threads of the shank, and a handle or lever for oscillating said toothed wheel; substantially as described. 50

3. In a cork-extractor, the combination with a frame or housing having a cylinder therein, 60 and a cap or plug for closing the upper end of said cylinder, of a screw-threaded shank working longitudinally in said cylinder having a reduced upper end for coöoperating with said cap or plug to limit the upward movement of the shank, a corkscrew-spiral forming a prolongation of the lower end of the shank, a longitudinally-movable nut through which said corkscrew-spiral works, held against rotation with said spiral, a toothed 70 wheel journaled in the frame or housing and meshing directly with the threads of the spiral shank, and a handle for oscillating said toothed wheel to move the shank and corkscrew-spiral longitudinally and to impart thereto a rotation when the longitudinal movement of the shank is resisted; substantially as described. 65

4. In a cork-extractor the combination with the frame or housing having a cylinder formed 80 therein and a worm-wheel journaled in said frame or housing with a handle for oscillating said worm-wheel, of a screw-threaded shank with which said worm-wheel meshes, located in said cylinder and adapted to move 85 longitudinally and to rotate therein, a corkscrew-spiral forming a prolongation of the said shank and arranged with its spiral at an opposite inclination to the teeth on the shank and a nut working in the lower end of the cylinder and surrounding said spiral with means for preventing the rotation of said nut; substantially as described. 90
